UNITED STATES PATENT OFFICE.

LOUIS ANGELUS, OF NEW YORK, N. Y.

STEAMING CABINET.

Application filed November 25, 1921. Serial No. 517,822.

To all whom it may concern:

Be it known that I, LOUIS ANGELUS, a citizen of the United States, and a resident of the city of New York, borough of Manhattan, in the county and State of New York, have invented a new and Improved Steaming Cabinet, of which the following is a full, clear, and exact description.

This invention relates to a steaming cabinet. An object of the invention resides in the provision of means whereby articles placed within the cabinet to be steamed are properly and effectually steamed without becoming wet.

15 Another object resides in the provision of means whereby the articles are effectually steamed on all sides and at all times.

A further object resides in the provision of means whereby the articles are kept out 20 of contact with the walls of the cabinet, to keep them dry, and whereby the water condensed from the steam is properly absorbed and prevented from coming in contact with the articles within the chamber.

25 A still further object resides in the provision of means whereby the condensed steam is guided along definite paths to prevent as much as possible the wetting of the inner surface of the cabinet.

30 Another object resides in the provision of means whereby when the door of the cabinet is opened the steam therein will not rush out into the face of the person opening the door.

35 A further object resides in the particular construction and arrangement of parts and various other features hereinafter described and claimed and shown in the drawings, which have been particularly designed to 40 make this cabinet one especially useful for this particular trade and, consequently, comprises a cabinet which requires a minimum expenditure of time and labor in its construction, together with a minimum required 45 amount of technical skill in the handling of the cabinet.

The invention is shown in the drawings, of which—

Figure 1 is a front elevation with the 50 lower corner of the cabinet broken away to show the construction of the water chamber.

Fig. 2 is a vertical longitudinal section through the cabinet.

The construction of cabinet shown in the 55 drawings is a preferred construction, al-

though it should be understood that certain modifications may be made in the construction and arrangement of the parts and in the character of the material used without departing from the spirit of the invention 60 as set forth.

This device comprises preferably a tall, slender cabinet made of stamped sheet metal 1 having a substantially rectangular cross section. This cabinet is closed at the bottom 65 and is supported by legs or pedestals 2. These pedestal are provided with flanged bars 3 connected thereto to support a plate 4. Around the sides between the legs 2 a sheet 5 is disposed and provided with perforations 6. Beneath the bottom of the cabinet and above the plate 4 a burner pipe 7 is disposed. This pipe has exterior of the cabinet a burner 8 connected to any suitable source of heating fuel, preferably gas. In 75 the bottom of the cabinet 1 a suitable quantity of liquid such as water 9 is disposed. Above the normal level of the liquid 9 a flange 10 is connected to the inner wall of the cabinet, and on this flange rests a perforated plate 11. This perforated plate may be provided with any suitable number of perforations and is preferably made of copper. Above this perforated plate 11 a plurality of slats or sticks 12 are disposed, preferably spaced above the plate 11 by means of side bars 12^a, which may be made of wood or other suitable material.

To the front of the cabinet, substantially on a level with the water chamber, I attach 90 a water-level gage 13 in the usual manner. This provides means whereby the amount of water within the receptacle at all times can be very readily ascertained. In these cabinets it is a very important feature to be 95 able to tell instantly whether there is sufficient water in the tank or chamber.

The metal of the cabinet itself is preferably turned over around the door aperture to provide a sort of U-shaped groove formed 100 by the flanges 14 and 15, as shown in Fig. 2. These flanges not only extend across the front and bottom of the door aperture but along the sides as well. At the top the groove thus formed provides a passageway 105 for any condensed steam which may trickle down the sides of the walls of the front of the cabinet, so that the inner face of the door does not become wet by reason of contact with this water. The door is made 110

preferably of two spaced layers 16 and 16^a of copper, spaced about an inch apart. This double door, therefore, provides a good heat insulation and at the same time tends to 5 make the door steamproof. The two layers of copper extend an inch or two beyond the opening around all the edges of the door whereby a very tight joint is made. The door 16 is provided with suitable hinges 17 10 and a pair of bracket plates 18 are disposed on the cabinet adjacent the movable free end of the door and are adapted to engage with locking levers 19 actuated by any suitable handle on a common actuating lever 20 in a 15 well-known manner. These brackets and locking levers are disposed equally distant from the top and bottom of the door, so that the door is most uniformly and effectively kept closed, whereby there is no leakage of steam. 20 Around the inner walls of the cabinet near the top of the door is a U-shaped frame 21, preferably of soft wood, supported on suitable flanged brackets 21^a. This frame not only provides spacing means for the rolls 25 of material 22 which are to be steamed and keeps them from contact with the walls, but also provides a surface of soft material which can absorb any condensed steam which may be formed in the upper part of the cabinet, so as to keep the roll from becoming 30 wet and thus diminishing the effectiveness of the steaming operation.

In the top of the cabinet and extending therefrom is a steam flue 23 normally closed 35 by a damper 24 fastened to a bar 25 which extends without the cabinet and is provided on the outer end with a handle 25^a. On the outer, upper face of the cabinet, beneath the damper, I provide a thermometer 22^a, 40 of any suitable design, to make it possible instantly to apprise the operator of the temperature within the steaming chamber, which knowledge at all times is very essential in the operation, since, especially, the 45 steaming of goods to be pleated depends essentially upon the maintenance for a definite time of exactly the right temperature. The top of the cabinet 26 is formed in a smooth, curved, semi-cylindrical shape and 50 is made of one sheet of metal such as 27 which is suitably connected at its opposite ends to the cabinet 1. Adjacent the upper end of the water chamber I provide a filling spout 28 having a cover 29 and disposed 55 adjacent an aperture 30 leading to the water chamber. The amount of liquid within the water chamber at all times, therefore, can be readily perceived from the gage 18 and instantly replenished when necessary by 60 means of the use of the filling spout 28, and removed by use of the faucet 13^a.

In the manipulation of steaming cabinets, it is sometimes desired to place therewithin articles wrapped up in rolls of paper or 65 other material, so that the pleats formed in

these articles can be made permanent there-in by the action of steam. However, the success of this pleating operation by the action of steam depends essentially upon the maintenance of a definite temperature 70 for a definite time within the chamber, and the successful commercial operation of the device depends largely upon the ease with which the ordinary operator, not necessarily very skillful, can control the device in all 75 its workings. Therefore, the provision of an easily controlled burner apparatus protected from draughts by, preferably, sheet metal, is very important. This sheet eliminates the danger of fire. The provision 80 of the water gage and the filling spout, whereby the condition of the water chamber and the filling thereof at any time can be very easily and quickly effected is also important. The provision of a circular top 85 enables a smooth, curved wall to be presented to the condensed steam whereby the water will flow down the side of the cabinet rather than drop off. By providing the damper, a person opening the door is merely 90 required to operate the damper before the door is opened to prevent steam from rushing out into his face, which has been highly objectionable in the use of cabinets heretofore. The provision of a thermometer connected to the interior of the steam chamber 95 is also important, in that the maintenance of a definite temperature for a given time is absolutely essential to the successful performance of the pleating. The provision of 100 means within the cabinet whereby the articles to be steamed are kept from direct contact with the walls and are prevented from being wet by the condensed steam, are additional features. All these features 105 combine to make a single unitary cabinet designed particularly to be highly efficient in the solution of these various problems, the solution of which has spelled success in the 110 operation of steaming cabinets.

What I claim is:

1. A steaming cabinet which comprises a casing having a steaming chamber in the bottom thereof, said casing adapted to receive rolls of material to be steamed, and a spacing frame mounted on and extending around the inner walls of the casing near the upper end thereof to maintain the rolls out of contact with the walls.
2. A steaming cabinet which comprises a casing having a liquid chamber in the lower end thereof, a perforated diaphragm above said chamber, a steaming compartment above said diaphragm, a flue in the top of the cabinet, a damper controlling the aperture 115 in said flue, a door through which articles to be steamed may be passed, a water-level gage connected to the front of the casing, a filling spout disposed at the side of the casing having a cover, and a thermometer dis- 120 125 130

posed on the front of the casing above the door to indicate the temperature within the steaming chamber.

3. A steaming cabinet which comprises a steaming chamber adapted to receive a plurality of rolls of material to be steamed, a frame of slats disposed in the lower portion of the chamber, said chamber having a liquid compartment beneath the frame, said frame adapted to support the rolls, and a spacing frame of wood mounted on and extending around the inner walls of the chamber near the upper end thereof to space the ends of the rolls away from the walls of the chamber.

4. A steaming cabinet which comprises a sheet-metal casing having a door-receiving aperture therein, metal around the aperture to form a spacing portion perpendicu-

lar to the wall of the casing and again bent to form a flange parallel to said wall, the groove formed between this flange portion and said wall adapted to receive moisture from the walls of the casing and prevent said moisture from coming in contact with the door.

5. A steaming cabinet which comprises a tall, slender casing of substantially rectangular cross section having a curved cylindrically shaped top, a steam exhaust extending from the top of the casing, a thermometer disposed in the front of the casing near the top thereof to indicate the temperature of the inside of the cabinet, and means formed of the material of the casing itself to receive moisture flowing down the sides of the cabinet.

LOUIS ANGELUS.
